UNITED STATES PATENT OFFICE

WILLIAM GENTRY SHELTON, OF ST. LOUIS, MISSOURI, ASSIGNOR TO SHELTON-JANCKE CORPORATION, OF EAST ORANGE, NEW JERSEY, A CORPORATION OF NEW JERSEY

HEATER FOR PERMANENT WAVE MACHINES

Application filed September 26, 1929. Serial No. 395,291.

This invention relates to machines for permanent waving and aims to provide certain improvements therein.

The invention is particularly directed toward the heating element which vaporizes the moisture surrounding each curl in order to produce the steam which is necessary for effecting the permanent waving operation. It has been proposed to utilize a transformer to step down the voltage of the ordinary commercial currents very materially so that the danger of burning from short circuiting is greatly minimized. By preference I use such a low voltage current (approximating one to three volts).

According to the present invention I form the heater as a flexible member which is capable of being used with practically any of the types of absorbent pads which are now in commercial use, and to this end I provide a heater which is constructed of flexible, non-inflammable material having a resistance unit incorporated therein, the resistance unit being of such degree of flexibility as to permit the heater to be wrapped around, or partially around, the curl to be treated. In the preferred form the resistance unit has terminals which extend to the exterior of the device, and which are bendable, but which are of sufficient rigidity to hold their positions when bent. Various other features of improvement will be hereinafter more fully described.

Referring to the drawings which illustrate one form of the invention:

Figure 1 is a plan of the improved heater.

Fig. 2 is a top or end view on an enlarged scale of the heater as applied to a curl.

Fig. 3 is a plan view of a combined heater and pad unit.

Referring to the drawings let A indicate the heater as a whole, which in its preferred form comprises two layers of flexible asbestos B between which is located the resistance material C. The resistance material C may consist of a flexible strip of metal which is preferably as non-elastic as possible so that it exercises little if any tendency to return to its original shape when the heater is wrapped around the curl. It will, of course, be under-

stood that it is the heater as a whole that is wrapped around the curl, and the particular formation of the heating unit may be varied so long as the heater has this capacity. It is best, however, if there is little tendency in the resistance material to spring back into flat form after it has been applied to the curl. In place of thin, flat metal, wire may be used, or such other metallic construction as will form a path for the current and have the necessary resistance to heat under the low voltages which it is preferred to use. If wire is used preferably the diameter is small, and if flat metal is used it is best made very thin.

Preferably the terminals D, D' are constructed of bendable conducting material joined to the resistance element, the terminals being by preference capable of retaining any position to which they are bent.

In use the device may be applied in any suitable manner to the curl. Fig. 2 illustrates a use according to the ordinary method of permanent waving wherein the hair is wound upon a curling rod beginning from the scalp end and continuing until the tip is wound. In Fig. 2, E designates a wrapping of flannel or other absorbent material which is first applied to the curl, and A indicates the heater as wrapped around the flannel being held in place by suitable metal clips or otherwise. I have preferred to use in association with the resistance element, a layer of aluminum or other foil in order to distribute the heat of the heater. When such a layer of foil is used, it is preferably inserted between the heater and the flannel or other absorbent material as at F. In this use the terminals D, D' will preferably be bent apart to avoid short circuiting. In the well-known Croquignole method of waving, the strand of hair is wound from the tip toward the scalp, and this requires a heater which is open at this side. In this instance the present device is wrapped around the moist flannel, or other absorbent material, with its sides toward the scalp, and the edges arranged on either side of the scalp end of the strand. In this use the terminals will ordinarily be bent at right angles to the heating element so as to extend away from the scalp.

The terminals are connected with the source of current, preferably by the usual wires G, G' which may lead to a switch section H designed to be plugged into the transformer or other source of electrical supply.

The heater provided by my invention forms a constituent part of the permanent wave machine, and is capable of indefinite use without renewal.

10 In Fig. 3 I have shown an extension of the present invention in which the heater is combined with a special construction of steaming pad unit by means of which very efficient results can be obtained.

15 In this figure the reference letter I designates a small piece of flannel, blotting paper, or other absorbent material, J is a sheet of paper which is connected to the flannel I, and K is a sheet of aluminum or other metallic foil the end of which should be well within the end of the pad, as at M, to avoid short circuiting the terminals of the heating element. In using the complete invention the heating unit A is placed on top of the foil and 20 the leaf of paper J is folded over the heater, whereupon the whole can be wrapped around the curl on the curler rod. The various layers of the pad unit may be fastened together by stitching or otherwise. In use that half 25 of the pad unit which carries the absorbent sheet may be dipped in the usual solutions so that the supply of moisture which is carried will suffice for the steaming treatment. In applying the device the heating unit and pad 30 unit as folded together may be applied as a single entity around the curl and clipped in place as hereinbefore described. The heater, hence, serves as a permanent device while the pad section is commonly utilized for a single 35 application and is then thrown away.

40 While I have shown and described one form of the invention it will be understood that I do not wish to be limited thereto, since various changes may be made therein without departing from the spirit of the invention.

45 What I claim is:

1. An electric heater comprising non-inflammable, nonconductive, sheet material, a heating element comprising a resistance unit 50 extended along and insulated by the same, and readily accessible terminals whereby the heating element may be connected in circuit with a source of electromotive force, the materials of which said heater is constructed 55 being such as to produce a finished article of the approximate thickness and flexibility of a sheet of medium weight wrapping paper and of a durability such as to adapt it for repeated use, said heater being of the approximate length and breadth of an absorbent 60 steaming pad used in the permanent waving of hair whereby it may be successively applied to each of a number of pads and wrapped therewith about the hair to be 65 treated.

2. A heater, as defined by claim 1, having its resistance unit incorporated in the body of the non-inflammable, non-conductive sheet material.

3. A heater, as defined by claim 1, of which the terminals are of bendable, conductive material of insufficient resiliency to return to any position from which they may be bent.

4. A heater, as defined by claim 1, of which the non-inflammable, non-conductive material comprises two parallel sheets of asbestos paper between which the resistance unit is enveloped, the material of the heater being such that it may be readily bent but of insufficient resiliency to return to any position from which bent.

5. The combination with a hair-waving steaming pad including a moisture holder, of a flexible, but non-resilient, electric heater comprising a thin sheet-like member of non-inflammable, non-conductive material of dimensions approximating those of the pad and having an electric resistance element extended along the same, said heater being readily applicable for use as a layer of the pad and readily detachable therefrom so as to be adapted for application to another pad.

6. The combination, defined by claim 5, of which the pad has a layer of impervious material to obstruct the escape of moisture vaporized by the heater.

7. The combination, defined by claim 5, including a heat distributor consisting of a layer of metal foil adjacent the resistance element but separated therefrom by the non-inflammable, non-conductive material.

8. The combination with a laminated hair-waving steaming pad including a sheet of absorbent material, a sheet of impervious cup of the plunger, and carry on their inner stitched together along one edge with the material, and a sheet of thin metal foil, and impervious material, of a thin, flexible, but non-resilient, sheet-like electric heater adapted to be readily inserted in the pad between the layers of foil and impervious material, and to be readily removed therefrom, said heater comprising parallel layers of asbestos paper, an interposed electrical resistance element, and terminals whereby the resistance element may be connected with an external circuit.

90 In witness whereof, I have hereunto signed my name.

100 WILLIAM GENTRY SHELTON.

CERTIFICATE OF CORRECTION.

Patent No. 1,883,828.

October 18, 1932.

WILLIAM GENTRY SHELTON.

It is hereby certified that error appears in the printed specification of the above numbered patent requiring correction as follows: Page 2, line 106, claim 8, beginning with the word "cup" strike out all to and including the article "the" in line 107; and line 108, after "foil," insert the words "stitched together along one edge with the sheet of foil between the sheets of absorbent"; and that the said Letters Patent should be read with these corrections therein that the same may conform to the record of the case in the Patent Office.

Signed and sealed this 6th day of December, A. D. 1932.
